United States Patent Office

Des. 183,035

Patented June 10, 1958

183,035

FAUCET SHELL OR SIMILAR ARTICLE

Stephen A. Young, Delphi, Ind.

Application November 1, 1956, Serial No. 43,641

Term of patent 14 years

(Cl. D91—3)

Fig. 1

Fig. 2

Fig. 3

Fig. 4

Figure 1 is a front elevational view of a faucet shell or similar article embodying my new design.

Figure 2 is a side elevational view thereof.

Figure 3 is a top plan view thereof.

Figure 4 is a bottom plan view thereof.

I claim:

The ornamental design for a faucet shell or similar article, substantially as shown.
